UNITED STATES PATENT OFFICE.

JAMES B. PORTER, OF YARMOUTH, NOVA SCOTIA, CANADA.

TRUNK-FIXTURE.

SPECIFICATION forming part of Letters Patent No. 404,111, dated May 28, 1889.

Application filed March 12, 1889. Serial No. 302,964. (No model.)

To all whom it may concern:

Be it known that I, JAMES B. PORTER, of Yarmouth, in the Province of Nova Scotia, Dominion of Canada, have invented a new 5 and Improved Trunk-Fixture, of which the following is a full, clear, and exact description.

My invention relates to an improvement in trunk-fixtures, and especially to the novel construction of a cover-stay.

The object of the invention is to provide a stay capable of convenient attachment to any trunk, whereby the lid or cover of the trunk, when carried upward to an open position at 15 a right angle to the body of the trunk, will be automatically locked to place.

A further object of the invention is to so construct the mechanism by which this result is accomplished that by a gentle downward 20 pressure upon the cover when in the open position the said cover may be readily closed.

The invention consists in the novel construction and combination of the several parts, as will be hereinafter fully set forth, and 25 pointed out in the claims.

Reference is to be had to the accompanying drawings, forming a part of this specification, in which similar figures of reference indicate corresponding parts in all the views.

Figure 1 is a perspective view of a trunk having the stay applied, illustrating the lid in a partially open position. Fig. 2 is a central vertical section illustrating the lid in a complete open position. Fig. 3 is a horizontal section on line $x-x$ of Fig. 2.

In carrying out the invention a recess, 10, is produced in the trunk-body 11, upon one inner end face, preferably near the top, and between the center of the said end and the 40 back, as shown in Figs. 1 and 3. In the forward end of the recess 10, which is ordinarily rectangular in general contour, one extremity of a spring-plate, 12, is secured, the other end of the plate, which is left free, being capable 45 of springing laterally outward from the recess, as best shown in Fig. 1. Upon the rigid or fixed end of the spring-plate, at or near the bottom, one extremity of a strap or keeper, 13, is fastened, which keeper at a short distance from this point of attachment is carried 50 outward at a right angle from the spring-plate, as illustrated at 14 in Figs. 1 and 3,

and diagonally upward to a rigid attachment to the inner face of the end piece of the trunk-body, a slight distance to the rear of 55 the recess 10. By reason of this formation of the keeper, it will be observed that the space between the latter and the spring-plate is gradually lessened from front to rear to such an extent that the free end of the spring-plate is capable of normal contact with the keeper.

A segmental strap or stay, 15, is secured to the inner end face of the cover 16 of the trunk, which stay passes down between the 65 keeper and the spring-plate, and is provided at its lower extremity with a diagonal lip, 17, adapted to engage with the bottom edge of the keeper when the trunk-lid is fully opened, as shown in Fig. 2.

I desire it to be understood that a stay may be provided for each end of the cover, if desired; but ordinarily a single stay is sufficient.

In operation, when the lid is closed, the lipped end of the segmental stay is carried 75 downward, essentially, to a contact with the bottom of the trunk. When the lid is almost fully opened, the lip of the stay contacts with the under edge of the keeper forward of the center, as shown in Fig. 1, and as the lid is 80 brought to a full open position the lip slides up the incline of the keeper until the lower end of the stay is jammed between the said keeper and free end of the spring-plate. Thus in this position the stay is rigidly supported by 85 frictional contact and sustains the lid at a right angle to the body of the trunk, as shown in Fig. 2.

Having thus described my invention, what I claim as new, and desire to secure by Letters Patent, is—

1. In trunk-fixtures, a lid or cover stay consisting of a spring-plate, a keeper secured to one end of said plate, capable of extending outwardly therefrom and contacting with the 95 opposite end, and a segmental bar adapted to be secured to the lid and sliding vertically and laterally between the keeper and the spring-plate and provided with a lip at the lower extremity, substantially as shown and 100 described.

2. In trunk-fixtures, a lid or cover stay consisting of a spring-plate, a keeper diagonally secured to one end of the plate, capable of ex-

tending outwardly therefrom and contacting with the opposite end of the plate, and a segmental bar adapted to be secured to the lid and having vertical and lateral movement between the spring-plate and keeper and provided with a diagonal lip at the lower extremity, substantially as shown and described.

3. The combination, with the body of a trunk having a recess produced in the inner end face and a lid hinged to said body, of a spring-plate secured at one end in the body-recess, a keeper secured to the fixed end of

the plate extending outwardly therefrom and transversely across the plate to a contact with the free end, and a segmental bar attached at one end to the lid and capable of passing downward between the keeper and spring-plate and provided at the lower extremity with a diagonal lip, substantially as shown and described.

JAMES B. PORTER.
